UNITED STATES PATENT OFFICE.

BURT S. HARRISON, OF CHICAGO, ILLINOIS, ASSIGNOR TO DRYING SYSTEMS, INC.,
OF CHICAGO, ILLINOIS, A CORPORATION OF ILLINOIS.

AIR HEATER.

Application filed August 24, 1922. Serial No. 584,016.

To all whom it may concern:

Be it known that I, BURT S. HARRISON, a citizen of the United States of America, and a resident of Chicago, county of Cook, 5 and State of Illinois, have invented a new and useful Improvement in Air Heaters, of which the following is a specification.

This invention relates mainly to air heaters, such for instance as may be used in connection with lumber kilns, paint shops, and other drying systems.

The main objects of the invention are to provide an improved form of air heating furnace or combination of burner, combustion 15 chamber, and oven, adapted to heat large quantities of air and capable of transferring substantially all of the heat from the flame and from the gases of combustion to the air to be heated before the gases of 20 combustion leave the heater; to provide a heater of the character described having a tortuous combustion chamber and passage-way diminishing in area of cross section to accord substantially with the diminished 25 volume of the air current as it cools in passing from the burner tuyère to the outlet, and so maintain a substantially constant flow speed; to provide an air heater of the character stated adapted to insure a steady forward 30 movement of the gases, free from appreciable eddy currents; to provide in such a heater a serially connected group of flue sections disposed horizontally one above another; to provide such a device adapted to 35 operate on either gaseous, liquid or pulverized fuel; to provide the necessary heater parts of simple form, adapted for ready forming as by casting, and adapted to prevent unequal expansion and injurious strains 40 under heat; to provide for ready access to the surfaces for inspection, cleaning and repairs; to provide joints such as may be depended upon to relieve the adjacent parts of expansion strains and yet be tight enough 45 to prevent leakage or infiltration; to provide wall members or sections of improved construction preferably in the form of castings, to enclose the combustion zone and adapted to receive a refractory material cemented 50 thereto, and without danger of breakage due to unequal expansion when under heat; to provide such a heater in standard unit sectional form so that its capacity may be made greater or smaller by the addition or subtraction of sections; and to provide for fir-

ing the larger units from both ends, with centrally disposed vertical passes.

An illustrative embodiment of this invention is shown in the accompanying drawings, 60 in which—

Fig. 1 is a vertical longitudinal section through the heater at 1—1 on Fig. 2 and shows the arrangements of baffles in the combustion chamber.

Fig. 2 is a vertical cross section through the heater at 2—2 on Fig. 1 and shows the combustion chamber and branched air flue disposed symmetrically within the air chamber.

Fig. 3 is an enlarged vertical section 70 through one of the horizontal joints of the fire chamber wall (see Fig. 2).

Fig. 4 is a fragmentary vertical section showing one of the removable fire plugs (see Fig. 1).

Fig. 5 is a horizontal section through one of the vertical joints of the heater and shows some of the extended heat distributing fins on the outside of the fire chamber wall.

Fig. 6 shows in vertical longitudinal section a large capacity embodiment of the invention, in which two fuel tuyères are disposed in opposition to each other for firing at both ends and in which the vertical passages are disposed alternately at the middle 85 and ends of the horizontal ways.

In the construction shown in the drawings, Figs. 1 to 5, the air heater as a whole comprises in combination, a burner in the form of a tuyère tube 1, a combustion chamber 2, the initial or lower section of which may be regarded as substantially a fire box, an air chamber 3 of flue like character surrounding said combustion chamber, and an outer insulating chamber 4 for dead air surrounding said air chamber together with certain structural members and details which will be described. The tortuous combustion chamber 2 extends upwardly in successive serially connected horizontal sections 5 separated by the baffles 6 and discharges its gases at the outlet 7. The air heating chamber or air flue 3 has an inlet 8 at the top on one side and dividing extends downwardly on both sides of the combustion chamber 2. The branches 9 unite at the bottom and discharge through the outlet 10 on the opposite side from inlet 8. Relative to the air passage 3 the outlet 10 is circuitously remote from the inlet 8, whereby a substantial heat-

ing time element is assured for the air to be treated.

Structurally the heater as a whole comprises an outer wall or casing 11 of heat insulating character, an air flue casing 12 of sheet metal, and the furnace proper made up mainly of cast wall plates and fittings to be described.

The said furnace or combustion part includes side wall sections 13, end wall sections 14 and top and bottom wall sections 15 and 16 respectively, all detachably fastened together by means of bolts 17 to form a flame and gas chamber.

Said chamber is lined with refractory plates 18 cemented to the inner sides of the said cast wall plates 13, 14 and 16 though at the top these lining plates may be omitted by reason of the lower temperatures of the fuel gas near the discharge end of the flue or chamber 2. The plates 18 have beveled edges as shown in Fig. 2 whereby grooves are provided to receive the edges of the baffles 6 for supporting the latter. The baffles also help to hold the plate 18 in place. The vertically spaced refractory baffles 6 divide the interior of the heater into the several horizontal gas passages 5 one above another, so as to retard the passage of the gases of combustion and provide a time element sufficient to permit the gases to discharge their heat through the wall plates 18 and 14, etc., to the downwardly moving air in air chamber 3.

The baffles 6, for the sake of uniformity in the size and shape of the wall plates, are equally spaced, but in order to provide for constant gas flow speed in the tortuous chamber 2 for the gradually cooling and contracting flue gases the walls 13 are made to converge upwardly, as shown in Fig. 2, whereby the fire flue sections range from a thick trapezoidal shape near the bottom to a thin shape of this character near the top. This form of flue is practically free from eddy currents and is highly efficient for the purpose here involved.

The walls of the combustion chamber are provided with flanges 19 adapted for fastening the cast metal plates together by means of the bolts 17. These flanges are spaced apart somewhat when the wall plates are assembled and the joint space between is mainly occupied by a snug fitting strip 20 which may be of cast iron and which is perforated, as at 21, to receive said bolts. In order to make the joint gas tight, a pocket is provided between the inner edge of strip 20 and the bottom of the space or groove between flanges, which pocket is occupied by a high temperature flexible packing 22, which may well consist of pure asbestos roving.

In order to provide for ready access to the interior of the combustion chamber, hand holes are provided which are normally

occupied by plugs 23. The inner end of each plug is bevelled to fit the correspondingly bevelled hole 24 of the furnace plates. The outer wall or casing plate is provided with a much larger hole 25 which is normally closed by a cover plate 26 secured detachably by screws 27. The plate 12 is provided with a hole 28 in axial alinement with the holes 24 and 25 and receives the plug 23 snugly therein. Said plate 12 is provided with exterior washers 29 fitting around the holes 28 and said washers being secured to bushings 30 by means of screws 31. The bushings 30 serve as spacers between the plates 12 and 14, see Fig. 4, and are secured to the latter by bolts 32.

The furnace plates are provided with extended radiating surface means in the form of fins 33 integrally therewith, which fins are disposed vertically as well, shown by Figs. 2 and 5.

Referring to Fig. 6, it will be seen that this invention may be embodied in a double burner furnace 34 provided with a plurality of horizontal flues 35, disposed one above another, and the lowermost being provided with two inlet tuyères, one at each end. The lowermost flue is provided with an outlet 36 in the middle of its upper wall. The second flue is provided with two outlets, one at each end 37. This arrangement alternates up to the top flue, which opens centrally into the discharge flue 38 leading to the stack, not shown.

It is to be understood that the general construction of the double burner heater is substantially like that of the single burner heater, except as above explained. It is provided with hand holes at one end to permit of access to the interior for cleaning, as in the single burner heater, and the various parts and sections are formed in substantially the same manner and are fastened together by bolts and screws in a demountable manner, as will be understood. In this instance the wall plates are made in five sections 39, though it is to be understood that this may be varied to suit the capacity required. For the sake of symmetry the number of sections may to advantage be an odd number, as for instance, 3, 5, 7, or 9, etc. Although but two specific embodiments of this invention are herein shown, it is to be understood that no attempt has been made to show all practical embodiments, and it is to be understood that some of the details may be altered or omitted, without departing from the spirit of this invention, as defined by the following claims:

I claim:

1. An air heater comprising, in combination a closed air chamber having an inlet and an outlet at points in effect remote from each other along the line of travel of the air and a furnace proper contained therein

including a fire box part and a combustion chamber merging therewith, said furnace being formed with upwardly convergent walls and being provided with horizontally disposed baffles spaced apart vertically, the convergence of the walls being adapted to accommodate a substantially constant velocity of the gradually cooling products of combustion, said furnace having an inlet for the fuel in its lower part and an outlet for the gases of combustion in its upper part.

2. An air heater comprising, in combination, an air chamber having an inlet and an outlet at points circuitously remote from each other, whereby a substantial heating time interval is provided for the passage of

each and every atom or unit of air through the heater and a furnace proper contained therein including a fire box part and a combustion chamber merging therewith, said 20 fire box and combustion chamber being conduit like in character and formed with horizontal baffles and upwardly convergent walls to maintain a substantially constant velocity of the gradually cooling and shrinking 25 products of combustion, said furnace having an inlet for the fuel in its lower part and an outlet for the gases of combustion in its upper part.

Signed at Chicago this 22nd day of Au- 30
gust 1922.

BURT S. HARRISON.
